UNITED STATES PATENT OFFICE.

JAMES McGLASHAN, OF YORK, PENNSYLVANIA, AND CARL ROBERT SWENSON, OF INDIANAPOLIS, INDIANA, ASSIGNORS TO MARTIN-PARRY CORPORATION, OF YORK, PENNSYLVANIA, A CORPORATION OF DELAWARE.

HINGE.

Application filed June 13, 1924. Serial No. 719,878.

To all whom it may concern:

Be it known that we, JAMES McGLASHAN, a subject of the King of Great Britain, residing at York, in the county of York 5 and State of Pennsylvania, and CARL ROBERT SWENSON, a citizen of the United States of America, residing at Indianapolis, in the county of Marion and State of Indiana, have invented certain new and useful Im- 10 provements in Hinges, of which the following is a specification.

The invention relates to improvements in hinges, particularly adapted for mounting swinging windows or windshields on stationary supports, but, of course, are applicable for use in various other fields where such a type of hinge is found to be desirable.

It is an object of the invention to provide a hinge for automobile windshields, and the like, having resilient friction means coacting with a pair of relatively movable hinge members to permit a movable windshield section to be engaged and adjusted 25 at will, and to firmly guide the same in its various positions of adjustment without manually loosening and tightening co-acting hinge parts.

More specifically the invention comprises 30 a hinge composed of a pair of stamped out hinge sections of a light structure, each having a concaved face portion and fastening parts projecting therefrom on each side of the face portion, with an interposed 35 star spring having a plurality of separated arms, the ends of which are adapted to alternately engage said hinge sections to frictionally hold one section in any adjusted position relative to the other.

40 The invention further aims to provide an inexpensive hinge utilizing stamped out parts which may be assembled with ease, and which hinge, though inexpensive to manufacture, is exceedingly efficient in use.

45 In the accompanying drawings we have shown the preferred embodiment of our invention, in which Figure 1 represents a view of the assembled hinge;

50 Figure 2 represents a view of the parts constituting the hinge in an unassembled condition; and

Figure 3 represents a detail view of the frictional star spring.

Referring now more particularly to the

drawings wherein like reference characters 55 indicate corresponding parts, the numerals 1 and 2 designate a pair of hinge members which are of identical construction. These hinge members are composed of struckout metal of any desired thickness depending 60 upon the use to which the hinge is to be placed.

Inasmuch as the hinge members are of the same construction a description of one 65 will apply equally to both and like reference characters will indicate similar parts in both of said members 1 and 2. Each hinge member is formed with a facing portion 3 that is concaved providing a cavity 70 therein for the reception of a frictional locking spring 4 to be later described. The concaved face portion of said spring member is further provided with a series of spaced sockets 5 arranged in circular relation around said face portion near its periphery. These sockets are preferably 75 formed by the use of punches or the like, and are of any desired depth. The shape of the sockets may also vary, but it is expedient that they be formed by means 80 of a punch. The sockets can be spaced apart any desired distance, depending upon the fineness of adjustment that a member supported by the hinge is to have. The face portion also has a central pivot aperture 6 extending therethrough adapted to receive a pivot bolt, rivet or the like by means of which adjacent sections are united together with the interposed frictional locking spring. It is to be observed that 90 the hinge section is formed of a stamping having diametrically opposed arms 7 projecting outwardly therefrom. These arms are formed with right angle flanges 8, each having apertures 9 therein, said 95 arms and flanges constituting attaching portions by means of which the hinge sections are united to a movable and a stationary part. From the description of the hinge section it will be apparent that it is stamped out from a single piece of metal, that it contains no attached or welded parts and it will furthermore be apparent that 100 the two sections of the completed hinge are interchangeable inasmuch as said sections 105 are of the same construction.

A pair of the sections that have just been described are united by means of the rivet

10, and interposed between said sections is the frictional locking star spring 4. This star spring is formed with a central aperture 4 spanning the rivet 10 and is housed 5 in the space between the face portions 3 of the hinge sections due to the fact that said face portions are concaved or dished. The star spring has a plurality of separated spring arms 11, six being shown for the 10 purpose of illustration, inasmuch as the hinge members in this disclosure are formed with twelve sockets representing the different adjustments that may be obtained through the use of this hinge. The spring 15 arms 11 of the star spring member radiate from the body 12 thereof, and said arms alternately project on opposite sides of said body 12. That is to say, one spring arm extends to the right of said body while the 20 next succeeding arm extends substantially to the left, as clearly shown in Figure 2. This means that the spring arms alternately engage the opposed face portions of the adjacent hinge sections and frictionally lock 25 said sections against relative movement. To obtain such a locking action each spring arm is provided near its outer end with a stamped out protuberance 13 adapted to form a rounded head in each spring arm to 30 engage in the sockets 5 provided in the face portions of each hinge section. It is therefore apparent that the spring arms are so arranged that the rounded protuberances enter the sockets in the adjacent face plates 35 and lock these sections frictionally against relative movement. When the desired pressure, however, is placed on the windshield or other movable element one spring section, 40 of course, moves relative to the other, compressing the spring arms and causing the protuberances at the ends thereof to engage other sockets arranged in the concaved face plates of said hinge members.

45 From the foregoing description of the parts of the hinge, it is thought that its operation and advantages will be apparent, but the same may be briefly recited as follows:

50 The hinge is composed of stamped out sections, the two hinge sections 1 and 2 being of the same construction and interchangeable. The face portions 3 of the hinge members 1 and 2 are dished and formed with aligned circular rows of sockets 5. The star 55 spring 4 is interposed between said members 1 and 2 within the enclosed space formed by dishing the face portions 3 of each hinge section. It will be apparent that when one of the hinge members is turned 60 this will compress or cause certain of the spring arms 11 to yield and the rounded protuberances at the ends thereof will ride out of certain sockets in the hinge sections and enter other sockets, of course, retaining 65 the movable shield section in any one of its

various positions of adjustment, the positions of adjustment being determined by the number of sockets in each face portion.

In operation it is, therefore, apparent that by engaging the shield and applying sufficient stress thereto the shield can be adjusted and the hinge is so constructed that when said shield is moved to any desired position it will remain in this adjusted position due to the action of the spring arms 11 and that no hinge parts need be manually loosened or tightened during the adjustment.

Having thus described our invention, what we claim is:

1. A hinge comprising a pair of hinge members having face portions adapted to lie side by side, a frictional locking element enclosed within a space between said face portions and having offset resilient means engaging each of said face portions to frictionally retain one hinge member in different adjusted positions relative to the other, and a pivot passing through said hinge members to unite them together. 80

2. A hinge comprising a pair of hinge members having dished facing portions adapted to lie side by side and to provide a space between said facing portions, an enclosed frictional locking element housed within said space, said element having spaced offset resilient means adapted to frictionally engage the inner surface of each facing portion to retain said hinge members in adjusted positions, and a pivot passing through said facing portions. 90

3. A hinge comprising a pair of hinge members each having an attaching portion, and a dished facing portion, the dished facing portions of the adjacent hinges extending in opposite directions and forming therebetween a housing space, a plurality of separated notches in each facing portion, a frictional locking element housed within the space between said facing portions, said locking member being provided with resilient means adapted to engage and coact with the notches in each of said facing portions, and means for holding said hinge sections together. 105

4. A hinge comprising a pair of hinge members each having an attaching portion, and a dished facing portion, the dished facing portions of the adjacent hinges extending in opposite directions and forming therebetween a housing space, a plurality of separated notches in each facing portion, a frictional locking element housed within the space between said facing portions, said locking member being provided with resilient means adapted to engage and coact with the notches in each of said facing portions, said resilient means comprising offset separated arms with protuberances on said arms at the ends thereof. 120

5. A hinge member comprising a pair of 130

- hinge sections of complementary structure, each section having a facing portion and an attaching part, separated notches disposed in circular formation in each of said face portions, a frictional locking member disposed between said facing portions, resilient arms carried by said locking member and extending alternately on each side of said member, protuberances at the outer end of 5 said arms, said arms being adapted to engage the sockets in each of said face portions to frictionally lock one hinge member in different positions of adjustment relative to the other, and a fastening device 10 adapted to hold said face members together.
6. A hinge comprising a pair of hinge sections, each having a dished facing portion and an attaching part, frictional locking notches disposed in each facing portion, a 15 frictional locking element housed in the space between said facing portions, said element being provided with a plurality of spring arms extending alternately on opposite sides thereof and provided with protuberances at the outer ends thereof, said 20 arms being adapted to engage the sockets in said face portions, and a pivot element uniting said hinge members and holding said opposed spring arms under tension.
7. A hinge comprising a pair of hinge member each having a face portion and an attaching portion extending therefrom, a 25 circular row of separated sockets in each facing portion, a star spring between said facing portions, the arms of said spring projecting alternately in opposite directions, a rounded protuberance at the outer end of 30 each spring arm, said protuberances being adapted to enter said sockets in said face portion to retain one of said hinge members in different adjusted positions relative to the other, and a pivot element for uniting 35 said hinge members and serving to hold said spring arms under tension.
8. A hinge comprising a pair of hinge sections composed of metal stampings of complementary structure, each section having a dished facing portion and an attaching part, separated notches disposed in circular formation in each facing portion, a frictional locking member disposed between said facing 40 portions and having separated resilient arms 45
- adapted to alternately engage said sockets in each of said face portions to frictionally lock the adjacent hinge members together, 50 and a fastening device cooperating with said facing members and adapted to hold said members together. 55
9. A hinge comprising a pair of hinge members composed of metal stampings having dished face portions and an attaching portion extending from each face portion at opposite sides thereof, separated sockets in each dished face portion disposed in a circular row, a friction member between 60 said face portions, spring arms projecting alternately on opposite sides of said friction member, rounded protuberances projecting from said spring arms on the sides thereof near the outer ends of said arms 65 adapted to enter said sockets in said face portions, and a pivot element uniting said hinge members and serving to hold said spring arms under tension. 70
10. A hinge comprising a pair of hinge sections, each having a facing portion and an attaching part, a frictional locking element housed between said face portions, said element being provided with a plurality of spring arms extending radially therefrom 75 with certain of said arms bent outwardly to one side of said locking element and other arms bent outwardly to the opposite side thereof to engage said facing portion to frictionally retain the hinge sections in different positions of adjustment. 80
11. A hinge comprising a pair of hinge sections, each having a dished facing portion and an attaching part, a frictional locking element housed in the space between 85 said facing portions, said element being provided with a plurality of resilient arms, certain of said arms extending on one side thereof and other arms extending on the opposite side of said frictional locking element, said arms being adapted to engage said facing portions, and a pivot element uniting with hinge member and holding said opposed spring arm under tension. 90
- In testimony whereof we affix our signatures. 95
